US009750317B2

(12) **United States Patent**
Ng

(10) **Patent No.:** **US 9,750,317 B2**
(45) **Date of Patent:** **Sep. 5, 2017**

(54) **HAND HELD LINK MAKING DEVICE AND KIT**

- (71) Applicant: **Choon's Design LLC**, Wixom, MI (US)
- (72) Inventor: **Cheong Choon Ng**, Novi, MI (US)
- (73) Assignee: **Choon's Design LLC**, Wixom, MI (US)
- (*) Notice: Subject to any disclaimer, the term of this patent is extended or adjusted under 35 U.S.C. 154(b) by 45 days.

(21) Appl. No.: **14/731,509**

(22) Filed: **Jun. 5, 2015**

(65) **Prior Publication Data**

US 2015/0265007 A1 Sep. 24, 2015

Related U.S. Application Data

- (63) Continuation of application No. 14/331,456, filed on Jul. 15, 2014, now Pat. No. 9,149,096, which is a continuation-in-part of application No. 13/626,057, filed on Sep. 25, 2012, now Pat. No. 8,899,631.
- (60) Provisional application No. 61/846,270, filed on Jul. 15, 2013.

(51) **Int. Cl.**

A44C 27/00 (2006.01)
A44C 5/00 (2006.01)

(52) **U.S. Cl.**

HAND HELD LINK MAKING DEVICE AND KIT

CROSS REFERENCE TO RELATED APPLICATION

This application is a continuation of U.S. application Ser. No. 14/331,456 filed Jul. 15, 2014, which is a continuation in part of U.S. application Ser. No. 13/626,057 filed Sep. 25, 2012, and further claims priority to U.S. Provisional Application No. 61/846,270 filed on Jul. 15, 2013.

BACKGROUND

This disclosure generally relates to method and device for creating a linked item. More particularly, this disclosure relates to a method and device for creating a linked wearable item from elastic bands.

Kits that include materials for making a uniquely colored bracelet or necklace have always enjoyed some popularity. However such kits usually just include the raw materials such as different colored threads and beads and rely on the individual's skill and talent to construct a usable and desirable item. Accordingly there is a need and desire for a kit that provides not only the materials for creating a unique wearable item, but also that simplifies construction to make it easy for people of many skill and artistic levels to successfully create a desirable and durable wearable item.

SUMMARY

A Brunnian link is a link formed from a closed loop doubled over itself to capture another closed loop to form a chain. Elastic bands can be utilized to form such links in a desired manner. The example kit and device provides for creation of Brunnian and other linked articles. Moreover, the example kit provides for the successful creation of unique wearable articles using Brunnian and other link assembly techniques.

The example kit includes a template for mounting an initial band and a hook utilized for attaching additional bands to the initial bands placed on the template. The template includes pins that hold the initial band in place while additional bands are linked onto each other. The kit further includes a clip utilized to attach ends once the desired length is formed.

These and other features disclosed herein can be best understood from the following specification and drawings, the following of which is a brief description.

BRIEF DESCRIPTION OF THE DRAWINGS

FIG. 1 perspective view of an example kit for creating a linked article.

FIG. 2 is schematic view of link article.

FIG. 3 is a schematic view of a series of a series of Brunnian links.

FIG. 4 is a side view of an example template.

FIG. 5 is an end view of the example template.

FIG. 6 is a top view of the example template.

FIG. 7 is a plan view of an example clip for securing loose ends of a Brunnian linked article.

FIG. 8 is perspective view illustrating elastic bands secured with the example clip.

FIGS. 9A-9M are views of an example method of creating a linked article using the example template and kit.

DETAILED DESCRIPTION

Referring to FIGS. 1 and 2, an example kit is indicated at 10 for creating linked items such as bracelets, necklaces and other wearable or decorative article as generally indicated in FIG. 2. The example kit 10 includes a template 12, a clip 16 and a hook 14. The example kit 10 also includes a number of elastic members 18 that are used with the kit 10 to form links for the resulting wearable article. The elastic members 18 are consumed as articles are fabricated, and are replaced and replenished with additional elastic members. Moreover, the example elastic members 18 are of a size corresponding with the example template 12. Further, although a single clip 16 is illustrated, the example kit 10 will include many clips 16 to provide for the fabrication of many articles 26.

Referring to FIG. 3, a Brunnian link 20 is formed from a continuous looped structure without forming an actual knot. Several links 20 are formed in a chain to form a circular structure. Ends 22 of each elastic member 18 are secured and 20 a durable wearable article is created. In this example three links 20 are shown forming a single chain. Each link 20 is formed by capturing the ends 22 of one loop structure with a mid portion 24 of another loop structure in series. Each link 20 depends on the previous and subsequent links 20 to 25 maintain the desired shape and integrity. Removing one link 20 results in all of the links becoming loose from each other.

Referring to FIGS. 4, 5 and 6, the example template 12 includes two posts 28A, 28B spaced a distance 30 apart from each other. Each of the pins 28A, 28B includes a first arm 32a-b and second arm 34a-b supported on a base 36. The arms 32a-b, 34a-b defines an access slot 38 that extends across both of the posts 28A, 28B. The base 36 includes a link opening 40 for completed links of a linked article during fabrication. Each of the first and second arms 32a-b, 34a-b 35 include upper and lower tabs 42 that maintain a linked article within a center section 44.

Referring to FIGS. 7 and 8, the example clip 16 is generally C-shaped with inwardly facing ends 48. The inwardly facing ends 48 point inwardly to an open space 50 40 where parts of the elastic members are kept. The inwardly facing ends 48 prevent ends 22 from sliding out from the inner area 50 off of the clip 16.

Referring to FIGS. 9A-M, the example template 12 is utilized for the formation of a linked article. As appreciated, 45 elastic bands 18 can be difficult to manipulate and hold during the construction of a desired article. The example template 12 provides for holding of an initial number of links 20 and subsequent connection of each link in the linked article. The template 12 includes the first and second posts 28A, 28B along with the access slot 38 across both of the posts 28A-B. The specific linked configuration can be a simple Brunnian link, but may also be more complex and intricate link structures such as a fishbone type link structure. The template 12 includes the link opening 40 to 50 facilitate the fishbone link structure where the linked article grows and extends from the template 12 through the link opening 40.

The Figures illustrate formation of a fishbone linked structure utilizing the example template 12. The initial step 60 illustrated in FIG. 9A includes assembling a first elastic band 18A by crossing over itself to form a FIG. 8 pattern across the posts 28A-B. A second elastic band 18B and third elastic band 18C is then assembled over the first elastic band 18A without crossing over as is shown in FIG. 9B. Three elastic bands are therefore supported across the posts 28A-B with the first band 18A on the bottom below the second and third elastic bands 18B, 18C.

Utilizing the hook tool 14, the bottom, lower most, or first elastic band 18A is pulled off of the posts 28A-B and looped over the second and third elastic bands 18B, 18C as is shown in FIGS. 9C and 9D. The first elastic band 18A is positioned to loop around each of the second and third elastic bands 18B, 18C and is not supported directly by the posts 28A-B.

An additional elastic band 18D is then added above the second and third elastic bands 18B, 18C such that the second elastic band 18B is now the lower most elastic band as is shown in FIG. 9E. The lower most elastic band 18B is then grasped with the hook tool 14 (FIG. 9F) by extending the hook tool 14 into the access slot 38 and grasping ends of the elastic band in sequence, pulling the ends away from the corresponding post (FIG. 9G) and looping each end over onto the and around the other links supported between the first and second posts as is shown in FIG. 9H.

An additional link is added above the two remaining links 18C, 18D across the two posts 28A-B as is shown in FIG. 9I and the process shown in FIGS. 9F through 9H is repeated with additional links to grow the length of the linked structure as is shown in FIGS. 9J and 9K until a desire length or number of links are connected to each other as is illustrated in FIG. 9L.

Once the desired length is achieved, as the example in FIG. 9L illustrates a clip 16 is attached to the end elastic link. The remaining links on the posts 28A-B can be removed and attached to the clip 16 to form the completed linked article as is shown in FIG. 9M. As appreciated although the ends are connected to form the example linked article. The linked article may have terminal ends that are separately terminated to provide a length of a linked article.

Accordingly, the example kit and method provide for the creation of many different combinations and configurations of linked structures and articles for the creation of bracelets, necklaces, and other wearable items. Moreover, the example kit is expandable to further create and expand the capabilities of potential linked structures and articles. Further, the example kit provides for the creation of such links and items in an easy manner allowing persons of varying skill levels to be successful in creating unique wearable items.

Although an example embodiment has been disclosed, a worker of ordinary skill in this art would recognize that certain modifications would come within the scope of this disclosure. For that reason, the following claims should be studied to determine the scope and content of this invention.

What is claimed is:

1. A kit for creating an item consisting of a series of links, the kit comprising:
  - a plurality of elastic bands, wherein each of the plurality of elastic bands comprise a closed loop; and
  - a template including at least two posts spaced apart from each other in a first direction, wherein each of the at least two posts includes a longitudinal channel bounded on three sides, a first tab near a top portion and a second tab near a bottom portion of the at least two posts for holding an elastic band across the at least two posts.
2. The kit as recited in claim 1, including at least one connector for securing an elastic band on one end of series of links to another elastic band on second end of the series of links.
3. The kit as recited in claim 2, including a base supporting the at least two posts, the base defining an open space between the at least two posts.
4. The kit as recited in claim 1, wherein the longitudinal channel on each of the at least two posts face in opposing directions.
5. The kit as recited in claim 4, wherein the longitudinal channel extends through the top surface of each of the at least two posts.
6. The kit as recited in claim 5, wherein the longitudinal channel opens to an outward facing side of each of the at least two posts.
7. The kit as recited in claim 1, including a hook for manipulating elastic bands held between the at least two posts.
8. A device for creating a linked article from elastic bands, the device comprising:
  - at least two posts spaced apart from each other and supported on a base, wherein each of the at least two posts include a longitudinal channel, a first tab spaced apart from a second tab for holding an elastic band therebetween, and a space defined within the base between the at least two posts and each of the at least two posts comprise a first arm and a second arm.
9. The device as recited in claim 8, wherein the base comprises a cylinder and the space is an opening through the cylinder.
10. The device as recited in claim 9, including a link opening on at one side of the cylinder to provide a space for linked elastic bands during fabrication of the linked article.
